UNITED STATES PATENT OFFICE.

WALTER C. WRIGHT, OF YOUNGSTOWN, OHIO.

GUARD FOR SAFETY CATCHES OF AUTOMATIC PISTOLS.

Application filed June 26, 1924. Serial No. 722,590.

To all whom it may concern:

Be it known that I, WALTER C. WRIGHT, a citizen of the United States, residing at Youngstown, in the county of Mahoning 5 and State of Ohio, have invented certain new and useful Improvements in Guards for Safety Catches of Automatic Pistols, of which the following is a specification.

This invention relates to improvements in 10 automatic pistols of the magazine type.

Pistols of the type referred to above ordinarily comprise a receiver which constitutes the frame of the firearm and which includes a hollow stock to receive the magazine 15 which is held in place by a catch which may be manually manipulated to permit of withdrawal of the magazine, and such firearms are usually so constructed that the said catch is exposed with the result that in 20 withdrawing the firearm from the pocket or a holster, the said catch is liable to so engage the pocket or some portion of the holster as to result in release of the magazine and its displacement either partially or wholly. 25 Therefore, the present invention has as its object to so construct the stock of an automatic pistol that the magazine catch will be protected in such a manner as to preclude any possibility of it being accidentally actuated to release the magazine. 30

In the accompanying drawings:

Figure 1 is a side elevation of an automatic pistol embodying the invention,

Figure 2 is a bottom plan view of the 35 stock end of the pistol,

Figure 3 is a vertical sectional view taken on the line 3—3 of Figure 2, looking in the direction indicated by the arrows,

Figure 4 is a detail vertical transverse 40 sectional view on the line 4—4 of Figure 3, looking in the direction indicated by the arrows.

In the drawings, the numeral 1 indicates in general the receiver of the firearm which 45 is provided with the usual chambered stock 2 into which is fitted the magazine which is indicated in general by the numeral 3. The numeral 4 indicates the usual slide which houses the barrel (not shown) and the numeral 5 indicates the usual trigger guard 50 for the trigger 6 and which guard constitutes a part of the receiver 2. The magazine 3 houses the usual elevating spring 7, and the magazine is provided with the usual side

wall 8, front wall 9, and bottom 10. In 55 carrying out the invention, the bottom 10 of the magazine will be formed somewhat thicker than usual and it will be provided in its under side with a recess indicated by the numeral 11, the thinned rear end portion of 60 the bottom resulting from the formation of this recess being indicated by the numeral 12, and constituting the equivalent of that portion of the bottom of the ordinary magazine which is engaged by the magazine catch 65 indicated by the numeral 13 and of the usual construction, the catch being held in engagement with the said thinned portion 12 of the bottom 10 by the usual spring 14 and having associated with it the usual grip 70 safety indicated by the numeral 15. These parts, with the exception of the bottom of the magazine, are of the usual construction but it has heretofore been the practice to leave the knurled head 16 of the magazine 75 catch 13 exposed to such extent that it is liable to come into contact with surrounding objects.

By reference now to Figures 1, 3 and 4 of the drawings, it will be observed that the 80 sides of the stock 2 of the receiver 1 are extended downwardly so as to have their lower edges substantially in marginal registration with the under side of the bottom 10 of the magazine 3 when the magazine is in place 85 and it will be evident, therefore, that these walls constitute side walls for the recess 11 completely housing the knurled head 16 of the magazine catch 13, the said lower extended portions of the side walls of the 90 stock being indicated by the numeral 17. By reason of this construction, the said knurled head or similar finger piece of the magazine catch will be completely housed in such a manner that it cannot accidentally come into 95 engagement with any surrounding objects although it may be readily actuated by inserting the finger into the recess and engaging the said head 16. Therefore, there is no likelihood of the magazine being released 100 when the weapon is quickly withdrawn from the pocket or a holster and which release, in the ordinary automatic pistol, renders the same useless.

The device embodying the invention is 105 especially useful when the pistol is carried in the pocket and particularly when carried in either side pants pocket, as in moving

about in the pocket its magazine catch, if arranged as is ordinarily done, would be liable to be shifted to release the magazine.

Having thus described the invention, what I claim is:

- 5 1. In an automatic pistol, in combination, a stock, a magazine removably arranged within the stock, the sides of the stock extending beneath a portion of the bottom of the magazine, and a catch for the magazine housed between the said sides of the stock and coacting with the said portion of the bottom of the magazine to retain the magazine in place within the stock.
- 5 2. In an automatic pistol, in combination, a stock including the usual magazine receiver, a magazine removably arranged within the stock and having a recess in its under side, the sides of the stock being extended downwardly beside the bottom of the magazine and at opposite sides of the recess whereby to provide a housing, and a catch for the magazine arranged between the said sides and within the said housing.

3. In an automatic pistol, in combination, 25 a stock including the usual magazine receiver, a magazine removably arranged within the stock and formed in its under side at its rear portion with a recess, the sides of the stock being extended downwardly and substantially in registration with the under side of the bottom of the magazine and extending at opposite sides of the recess, and a catch coacting with the wall of the recess and housed within said wall and between the said sides of the stock. 30

4. In an automatic pistol, in combination, 35 a stock, a magazine removably arranged within the stock, and a catch for the magazine coacting with a portion of the bottom of the same to retain the magazine in place within the stock, the stock having a portion extending below the said catch and the said portion of the bottom of the magazine and housing the said parts. 40

In testimony whereof I affix my signature.

WALTER C. WRIGHT. [l. s.]
